UNITED STATES PATENT OFFICE

91,675

DESIGN FOR A PENCIL SHARPENER

Raymond Loewy, New York, N. Y.

Application May 29, 1933, Serial No. 48,231

Term of patent 3½ years

To all whom it may concern:

Be it known that I, RAYMOND LOEWY, a citizen of the Republic of France, residing at New York, in the county of New York, in the State of New York, have invented certain new, original, and ornamental Design for Pencil Sharpener, of which the following is a specification, reference being had therein to the accompanying drawing, forming a part thereof, wherein:

I claim:

The ornamental design for a pencil sharpener substantially as shown.

RAYMOND LOEWY.
